UNITED STATES PATENT OFFICE

103,216

DESIGN FOR A BATHING MAT FOR INFANTS

Edmund D. Cevasco, Akron, Ohio

Application September 30, 1936, Serial No. 65,072

Term of patent 14 years

To all whom it may concern:

Be it known that I, Edmund D. Cevasco, a citizen of the United States, residing at Akron, in the county of Summit and State of Ohio, have invented a new, original, and ornamental Design for a Bathing Mat for Infants, of which the following is a specification, reference being had to the accompanying drawing, forming part thereof.

I claim:

The ornamental design for a bathing mat for infants as shown.

EDMUND D. CEVASCO.
